HAND GRIP FOR BOTTLES OR THE LIKE

Samuel Perun, 2211 NE, 135th Lane, North Miami, Fla.

Filed May 9, 1963, Ser. No. 74,832

Term of patent 14 years

(Cl. D58—26)

FIG. 1

FIG. 2

FIG. 3

FIG. 4

I claim:

The ornamental design for a hand grip for bottles or the like, as shown.
